UNITED STATES PATENT OFFICE.

PERRY NOUN, OF BUFFALO, NEW YORK.

PHOTOGRAPHIC-PRINT-DRYING MACHINE.

Application filed August 20, 1925. Serial No. 51,457.

My invention relates to improvements in photographic print drying machines, and the object of the invention is to devise a machine having a rotatable member in which

5 a plurality of print drying racks are supported, the rotatable member being enclosed in a suitably heated casing. A further object of the invention is to provide a closable receptacle in which the print drying racks 10 may be placed upon their removal from the rotatable member, means being furnished for conveying the hot air from the casing of the rotatable member to the aforementioned receptacle and from thence back into 15 the casing. A still further object of the invention is to devise means whereby the machine operator may remove either a complete rack or individual plates, the prints being placed upon such plates for drying.

20 My invention consists of a photographic print drying machine constructed and arranged all as hereinafter more particularly described and illustrated in the accompanying drawings in which:

25 Fig. 1 is a side elevational view of my machine, the casing being broken away to disclose the rotatable rack supporting member, which is also partly broken away.

Fig. 2 is a front elevational view thereof.

30 Fig. 3 is a perspective view of a broken away portion of the machine showing the receptacle for receiving the racks when they are removed from the rotatable member.

Fig. 4 is a perspective view of the rotatable member removed from the machine.

35 Fig. 5 is a perspective view of one of the racks.

Fig. 6 is a perspective view of one of the plates upon which the prints are placed; a 40 plurality of these plates are positioned in each rack.

Like characters of reference indicate the corresponding parts in the different views.

1 is a hollow rotatable member of cruciform formation, being constructed of sheeting supported upon a plurality of angle irons 2 which are built about a central web 3 in which is secured a transverse shaft 4 which protrudes from each side of the member 1. The driving racks consist of upper and lower parallel spaced apart plates 5 and 6, such plates being corrugated and held in relation to one another by the four posts 7. 50 8 are rectangular plates upon which the 55 prints 10 are placed to dry, a plurality of these plates being inserted into each rack,

being held in a vertical position and spaced apart by the corrugations 5 and 6 in the plates.

Longitudinal guides 11 are positioned centrally in the member 1 and constitute with respective pairs of angle irons 2 runners between and upon which the racks are supported, two racks being inserted into each arm of the member 1. The racks are 60 secured in the arms of the member 1 by bars 12 which are hinged to one side of the member, their ends being bent inwardly and adapted to clip over suitably positioned pins 13 upon the other side of the member 1. 70

The rotatable member 1 is mounted in a casing 14, the protruding ends of the shaft 4 being journaled in bearings 15 centrally positioned in the sides of the casing 14. Upon one end of the shaft 4 which extends 75 through its bearing 15 a gear 16 is provided, and adapted to mesh with a pinion 17 upon the armature shaft of an electric motor 18 which is positioned upon the outside of a casing 19 which encloses the gear and pinion. 80 20 is a foot operated switch for controlling the electric motor and consequently the rotations of the member 1.

On the front of the casing 14, I provide an 85 aperture closed by a sliding door 21 mounted in a pair of vertically positioned guides 22 on the outside of the casing, the aperture being positioned on the same level as the center of the member 1. Positioned at the bottom of the door 21 and extending beyond 90 one side of the machine a table 23 is furnished, its outer edge being supported upon legs 24, and its extended portion adapted to carry a rack receiving receptacle 25. This rack receiving receptacle has two slidable 95 doors 26 and 27, the door 26 being at right angles and adjacent to the door 21 in the casing, the other door 27 being at right angles to the door 26, as is clearly shown in 100 Figure 3.

A pair of electrical elements 28 are positioned in a recess 29 in the bottom of the casing 14, and constitute the means for heating the interior of the casing for drying the prints, the heated air being sucked 105 upwardly through the arms of the member 1 by means of the fan 30 which is positioned in an orifice 31 in the top of the casing, such orifice opening into a hot air pipe 32 which extends into the top of the receptacle 25. 33 is a further hot air pipe extending 110 from the bottom of the receptacle 25 to the

lower portion of the casing 14, the lower floor of the receptacle having perforations 34 for permitting the air to enter the lower pipe 33.

5 My machine is operated as follows:

The current is turned on in the electrical elements 28 thus heating the air in the casing 14, the suction fan 30 is now rotated by means of the electric motor 35 and the 10 hot air is drawn upwardly into the pipe 32 from where it passes down into the receptacle 25, passing from thence through the pipe 33 back into the casing 14 where it is reheated. The prints are placed in the usual 15 manner upon the plates 8, the plates being inserted into the racks, the racks are in turn inserted into the open ends of the arms of the member 1, a rack being put in one side of each arm when this is done a second 20 rack is inserted in each arm. The member 1 is now rotated for a certain length of time and the first rack that was put in is now taken out and is placed by the operator in the receptacle 25, the door 26 being 25 opened for this purpose, thus in the interval between the time when the racks are taken from the machine until the prints are about to be removed from the plates, the 30 prints are in a further drying compartment which will completely dry any prints that may be slightly damp.

By opening the door 27 the racks may be removed from the receptacle 25 without disturbing the operation of the machine.

35 When it is desired to remove some of the plates from the racks it is merely necessary to swing the bar 12 open and pull the required plates out of the rack, the bar 12 being swung into position before the member 1 is again rotated.

From the above description it will be seen that I have devised a very simple and effective machine for drying photographic prints which is simple and quick in operation. Furthermore by always removing the racks at the same position it has been made possible to provide the table for sliding the racks onto when they are removed from the machine thus obviating the necessity of lifting the loaded racks by the operator as is very often the case with these machines. By the use of the receptacle 25 a thorough drying of the prints is insured as they are exposed to the heated air until the moment 55 that they are removed from the plates.

What I claim for my invention is:—

1. A photographic print drying machine comprising a casing, a print containing member mounted in the casing, air heating means positioned in the casing, a print re-

ceiving receptacle in the vicinity of the casing, and means for conveying the hot air from the top of the casing and injecting it into the print receiving receptacle.

2. A photographic print drying machine, 65 comprising a casing, a print containing member mounted in the casing, air heating means positioned in the casing, a print receiving receptacle in the vicinity of the casing, means for conveying the hot air from 70 the top of the casing through the print receiving receptacle, and from thence back into the lower portion of the casing.

3. A photographic print drying machine, 75 comprising a casing, a print containing member mounted in the casing, air heating means positioned in the casing, a door in the casing giving access to the print containing member, a table underneath the door, a print receiving receptacle mounted 80 on the table adjacent to the door, means for conveying the hot air from the top of the casing through the print receiving receptacle, and from thence back into the lower portion of the casing.

4. A photographic print drying machine comprising a casing, a rotatable print containing member mounted therein, print containing drying racks adapted to be inserted into the rotatable member, print containing plates adapted to be inserted into the drying racks, and unitary means for locking the racks and plates in place in the rotatable member.

5. A photographic print drying machine, 95 comprising a casing, a print containing member mounted in the casing, air heating means positioned in the casing, a door in the casing giving access to the print containing member, a table underneath the 100 door, a print receiving receptacle mounted on the table adjacent to the door, a pair of doors in the print receiving receptacle, one of said doors being adjacent to the door in the casing and through which the prints are 105 inserted into the print receiving receptacle, the other door constituting means through which the prints are removed from the print receiving receptacle.

6. A photographic print drying machine, 110 comprising a casing, a print containing member mounted in the casing, air heating means positioned in the casing, a door in the casing giving access to the print containing member, a table underneath the 115 door, a print receiving receptacle mounted on the table adjacent to the door, and means for conveying the hot air from the casing into the print receiving receptacle.
